UNITED STATES PATENT OFFICE

157,541

MATTRESS

Paul Spagnoli, San Francisco, Calif.

Application May 10, 1948, Serial No. 146,255

Term of patent 14 years

(Cl. D5—2)

To all whom it may concern:

Be it known that I, Paul Spagnoli, a citizen of the United States, residing in the city and county of San Francisco, State of California, have invented a new, original, and ornamental Design for a Mattress, of which the following is a specification, reference being had to the accompanying drawings, forming part thereof, in which:

Figure 2 is a side elevation of my mattress (both sides are identical with one another); and tress (both ends are identical with one another).

The bottom face of the mattress is plain.

I claim:

The ornamental design for a mattress, substantially as shown and described.

PAUL SPAGNOLI.
